UNITED STATES PATENT OFFICE.

WILLIAM W. CLARK, OF CHICAGO, ILLINOIS.

SAND-DRIER.

SPECIFICATION forming part of Letters Patent No. 278,883, dated June 5, 1883.

Application filed January 29, 1883. (No model.)

To all whom it may concern:

Be it known that I, WILLIAM WILLIS CLARK, a citizen of the United States, residing at Chicago, in the county of Cook and State of Illinois, have invented certain new and useful Improvements in Sand-Driers, of which the following is a full, clear, and exact description, sufficient to enable others skilled in the art to which my invention appertains to make and use the same.

My present invention has for its object to provide an apparatus for drying sand and like material, which shall be simple and durable in its parts, shall be of such construction that the heat of the fuel will be most economically and effectively applied, and in which the drying operation will be quickly and thoroughly accomplished.

A further object of invention is to furnish means whereby the same apparatus may be used for drying both sand and gravel.

These objects of invention I have accomplished by the mechanism hereinafter described, particularly pointed out in the claims, and illustrated in the accompanying drawings, in which—

Figure 1 represents a view in side elevation, parts being broken away for better illustration. Fig. 2 is a view in transverse vertical section. Fig. 3 is a view in front elevation, and Fig. 4 is a plan view, of the drier. Fig. 5 is a detailed sectional view.

A designates the base of the drier, which is supported upon suitable legs, and consists of an oblong casting having a flanged bottom, a, and an open front which abuts against and is securely bolted to the face-plate B, provided at its lower portion with the door a', for the withdrawal of ashes, and centrally with the fuel-charging door b.

Upon the inner side of the base A are formed the end lugs, a'', and the broad central lugs, a'', which serve to sustain the ends of the grate-bars A', formed of two separable parts, as shown. The grate-bars A' are located at a slight distance below the top of the casting, so that the flame and heat of the burning fuel

will be more effectively applied to the base of the fire-dome C than would be possible were the grate-bars upon a level with the top of the casting, as in the latter case any fresh or spent fuel banked against the bottom of the dome

would prevent the uniform and perfect heating of the same.

The dome C, which constitutes the top of the fuel-chamber, is preferably formed of plate-iron with inclined back c and broad inclined sides c', the abutting edges of the back and sides being bolted firmly together, as shown. The front ends of the sides c' fit within grooves 60 formed in the lugs b', cast upon the rear side of the face-plate, and a constantly-tight joint is thus secured between the face-plate and the dome. A space is cut in the upper portion of the back of the dome, around which is bolted 65 a casting, C', shaped substantially as shown, to which will be fitted the smoke-pipe of the fuel-chamber. The bottom edge of the dome C rests within the groove or channel d at the lower portion of the rim D, which extends 70 around the sides and back of the drier. This rim, preferably formed of cast metal, is provided also with the channel d', in which fits the upper edge of the base A, and with the channel d'', in which rests the bottom of the 75 hopper E. The inclined sides and back of the rim D are furnished with discharge-perforations d', and with the square discharge-openings d'', which are closed by the perforated gates or slides D', passing through suitable slots 80 formed in the upper edge of the rim D, and furnished with handles d'' for their ready withdrawal. The rim D is secured to the face-plate by bolts passing through the lugs or ears d'', and constitutes the inclined bottom of the 85 hopper E, which is sustained thereby, the inner walls of this hopper being formed by the inclined sides and back of the dome C. The front edges of the sides of the hopper are securely bolted, as shown, to the rearwardly-extending flanges b'', which are cast upon the back of the face-plate B.

From the above-described construction it will be seen that the dome and hopper are firmly held in proper relative position and 95 upon the base by means of the grooved rim D, and together form the back and side spaces within which the material to be dried must be placed.

When sand is to be dried it is charged into 100 the hopper, the fuel is lighted, and as the drying progresses the sand flows from the discharge-orifice of the rim and gates. By inclining, as shown, the walls of the fire-dome not

- only is the heat of the fuel more directly and economically applied, being compelled to impinge against the walls, but the banking of the sand is also effectually prevented.
- 5 When my improved apparatus is to be used for the purpose of drying gravel, the gravel is placed within the hopper, the gates being in closed position, and allowed to remain there until sufficiently dried or heated. The gates will 10 then be raised and the gravel will be discharged through the large square openings of the rim. As in certain classes of work for which sand-driers are commonly employed it frequently becomes necessary to dry gravel, the advantage of having the discharge-gates must be apparent, and by providing these gates with perforations, as shown, the dry sand will flow readily through them, and they need only be removed when dried gravel is to be discharged.
- 15 It is obvious that my improved drier may be modified within wide limits without departing from the spirit of the invention. Thus, for example, hinged doors may be used instead of the perforated gates in the bottom of the hopper, and when gravel is to be dried or heated the dome may, if desired, be formed of 20 perforated plates. I do not wish therefore to be understood as limiting myself to the precise details of construction set forth.
- 25 Having thus described my invention, what I claim as new, and desire to secure by Letters Patent, is—
1. A sand-drier having a fuel-chamber provided with a dome having inclined sides, a hopper or casing surrounding said dome, and 30 a rim having an inclined perforated face constituting the bottom of said hopper, said rim being formed separate from said hopper and connected thereto, substantially as described.
2. In a sand-drier, the combination of a 40 fuel-chamber provided with a dome having inclined sides, a hopper surrounding said dome, and a grooved rim for supporting said dome and hopper, and having inwardly-inclined perforated sides, substantially as described. 45
3. In a sand-drier, the combination, with a fuel-chamber, of a hopper or casing, a bottom for said hopper having large openings for the free discharge of gravel, and smaller openings for the discharge of sand, and having gates 50 for said large openings, provided with perforations therein of a size adapted to permit the passage of sand and arrest gravel, substantially as described.
4. A sand-drier embodying in its construction a base forming an ash-pit, a grooved rim resting on said base and provided with inclined perforated sides, a dome resting on said grooved rim, a hopper surrounding said dome upon three sides, and a face-plate forming the 60 front of the base, the dome, and the hopper, substantially as described.
5. In a sand-drier, the combination, with the base, of the fuel-chamber having a dome and the face-plate provided with grooved lugs to 65 receive the edges of said dome, substantially as described.
6. The combination, with the base A and inclined dome C and hopper E, of the inclined perforated rim D, having grooves d , d' , and d'' 70 to receive, respectively, the edges of the base, the dome, and the hopper, all combined and arranged substantially as described.

WILLIAM W. CLARK.
